(57) CLAIM

We claim the ornamental design for a can drainer, as shown and described.

DESCRIPTION

FIG. 1 is a top, perspective view of a can drainer showing our new design;

FIG. 2 is a top view thereof;

FIG. 3 is a front side view thereof;

FIG. 4 is a right side view thereof;

FIG. 5 is a bottom view thereof;

FIG. 6 is a bottom, perspective view thereof; and,

FIG. 7 is a cross-section view thereof taken along line 7-7 in FIG. 2.

Any surfaces of the design not shown, including interior surfaces, form no part of the claimed invention.

1 Claim, 6 Drawing Sheets
